UNITED STATES PATENT OFFICE

2,554,220

POWER-OPERATED SELF-ANCHORING
TREE-CUTTING TOOL

Thomas Stennitt, Lansdowne, Ontario, Canada

Application October 11, 1946, Serial No. 702,725
In Canada March 5, 1945

4 Claims. (Cl. 143—68)

1

This application is a continuation-in-part of application Serial No. 604,652, now abandoned, filed July 12, 1945.

This invention relates to sawing machines, and more particularly to the portable tree or log cutting type.

It is an object of this invention to provide a simple, lightweight sawing tool, of low cost manufacture, which may be transported and operated conveniently by one man, which may be quickly and readily clamped in firm operating position on portions of a log or tree of a wide range of sizes and shapes and substantially regardless of the distance of such portions from the ground, and which when so positioned may be actuated to complete the sawing operation with little or no attention of the operator.

To this end, the invention contemplates the provision of a tree or log cutting tool comprising a frame, sawing mechanism mounted on the frame, a motor for driving such mechanism mounted on the forward end of the frame, a clamping member for engagement with a tree or log mounted on the forward end of the frame below the motor, and a second clamping member pivoted to the rearward portion of the frame and having a portion lying directly below the forward portion of the frame for cooperation with the first clamping member. The invention further contemplates a novel arrangement of parts and driving mechanism whereby the device may be easily handled and conveniently operated with a minimum of skill.

Other objects, advantages and details will become evident as the description proceeds with particular reference to the accompanying drawing, in which—

Figure 1 is a side elevation of the tool in accordance with the invention,

Figure 2 is a plan view;

Figure 3 is an end elevation;

Figure 4 is a detail view in partial sectional elevation of a loading means for the saw;

Figure 5 is a partial bottom plan view showing a detail of the clamping means, and;

Figure 6 is a partial sectional end elevation showing a clutch actuating mechanism.

In the drawing, the frame 1 comprises a longitudinally extending member 2, preferably in one-piece U-shaped form of light tubular metal, a plurality of transverse bars 3, an upwardly extending U-shaped member 4 fixed to the forward end of member 2, and a longitudinally extending rod 5 having one end fixed to the upper portion of member 4 and its other end connected to the rearward portion of member 2, the rod 5 serving as a convenient carrying and handling means for the device.

2

A motor 6 is carried by the extreme forward end of the frame and preferably offset from the longitudinal axis thereof. In order to permit operation of the device in either upright or inclined position of varying extent, mounting means is provided for the motor whereby it may be conveniently placed in upright position despite varying angularity of the frame. Such mounting means comprises a support 7 having a base plate 8 to which the motor is secured and arcuate end plates 9 at right angles to the base. The plates 9 have arcuate slots 10 therein and, at the inner end of the support, pins 12 carried by a transverse bar 3 extend through the adjacent slot in sliding relation thereto to carry the support. At the outer end of the support, pins 11 carried by the outer transverse bar 3, extend in sliding relation through the adjacent slot to carry the support. The pins 11 are provided with lock nuts 13 to lock the support in any desired position with relation to the frame.

The driving shaft 14 of the motor is provided with a pulley 15, which is coupled by means of a clutch 16, with a stub shaft 17 mounted in bearings 18 below the frame. While any suitable clutch may be employed, that shown is of simplified and effective construction. The stub shaft 17 is provided with a pulley 18, and a belt 19 normally loosely engages pulleys 15 and 18 to permit free running of pulley 15. Pulley 18 is of considerably larger diameter than pulley 15 to provide a speed reduction between shafts 14 and 17 of, for instance, 2 to 1. Belt-tightening means to cause driving engagement of the belt 19 with the pulleys comprises a roller 20, rotatably carried by an arm 21 pivoted to the frame at 22, and a lever 23, pivoted to the frame at 24, for imparting swinging movement to the arm. The lever is connected to arm 21 by means of a second arm 25 fixed to arm 21 by means of bolt 26 and having its free end connected by spring 27 to pin 28 on the lever. The pressure applied to arm 21 and roller 20 by the lever may be adjusted by loosening bolt 26 and adjusting the position of arm 25 with respect to arm 21. The lever is held in any position to which it is moved by frictional engagement of the pin 28 with the walls of a slot 29 in a link 30, one end of which is pivoted to an upright post 31 on the frame and the other end of which is connected by means of a spring 32 with the frame.

Stub shaft 17 is geared, by means of gears 33 and 34, to parallel driven shaft 35, mounted in bearings 36 suspended from the frame. The ratio of gears 33 and 34 is such as to provide a speed reduction of, for instance, 2 to 1.

The driven shaft 35 extends to a point adjacent the rearward end of the frame, where it has driv-

ing engagement with a transverse shaft 37 by means of bevel gears 38 and 39. The ratio of gears 38 and 39 is such as to provide a speed reduction of, say, 5 to 1. A protective cover 41 may be provided for the upper portion of gear 39 and a depending frame member 42 acts as a guard for the lower portion of the gear. Shaft 37 is journalled in suitable bearing blocks 40 carried by the frame.

One end of shaft 37 extends beyond the frame and a crank arm 43 is fixed to such end of the shaft. A pitman 44 is pivotally connected to the outer end of the crank arm and to a carriage 45 reciprocally carried by an auxiliary frame 46 which is pivotally mounted at one end on the shaft 37 by means of a sleeve 59 to which the frame is fixed and which is journalled on shaft 37. The frame 45 preferably comprises a light tubular metal rod 47 of U-shaped form, the parallel arms of which constitute tracks for engagement by the grooved peripheries of rollers 48 of the carriage. The carriage comprises a plate 49 in which are journalled the shafts 50 of the rollers. Preferably, two pairs of aligned rollers are provided, two of which engage the upper track and two of which engage the lower track.

A drag saw 51 is mounted on the plate 49 by means of bolts 52. The saw extends through a gauge block 53 carried by the free end of the auxiliary frame. When not in operation, the free end of the auxiliary frame may be supported on the main frame by means of a laterally projecting member 54 on the main frame on which an opposed projection 55 on the auxiliary frame is adapted to rest. The member 54 is carried by an upwardly curved frame member 56 fixed to one of the arms of U-shaped member 2. The member 56 may be additionally supported by the posts 57. A handle 58 for lifting the free end of the auxiliary frame may be provided.

An important feature of the invention resides in the provision of loading means for the saw to minimize the operator's attention during the sawing operation and to facilitate and improve the latter operation. As is well known, in sawing devices of the present type, it is substantially essential for the operator to apply pressure manually to the sawing frame during the cutting operation to ensure satisfactory cutting and to eliminate harmful vibration. The present invention seeks to eliminate this step by providing an adjustable saw loading device which comprises a sleeve 59, fixed to shaft 37 adjacent the auxiliary frame and a segmental frame 60 fixed to the sleeve. Pivoted to the base of the segmental frame is a lever 61 which has engagement with one or other of teeth 62 on the periphery of the segment. A spring 63 is connected at one end to the free end of the lever and at the other end to the main frame member 56. It will be apparent that the spring, acting through the lever and sleeve, will exert a downward swinging action on the auxiliary frame about its pivot on the shaft, the force of such swinging action being adjustable by the setting of the lever in the toothed segment. Thus, a downwardly acting pressure will be exerted on the saw to maintain it in satisfactory cutting relation with respect to the log during the forward stroke and to eliminate vibration during the return stroke. The usual means is provided for permitting substantial disengagement with the work piece during the return stroke of the saw, such means comprising the small crank 64 in the shaft 37.

Means for clamping the device to a tree or the

like for entire support therefrom comprises a downwardly projecting spike 65 fixed to the forward end of the main frame adjacent one side thereof, a second downwardly projecting spike 66 carried by an arm 67 pivoted to a bracket 68 mounted on the lower side of a transverse bar 3. Several pairs of positioning lugs 69 are provided on the lower surface of the transverse bar 3 at the forward end of the frame whereby the arm 67 and spike 66 may be placed in several positions at various distances from the fixed spike 65 to facilitate clamping engagement with various sizes and shapes of logs or trees. A spring 70 maintains the arm in engagement with the bar. A complementary clamping member comprises the arm 71 having a yoke 72 pivotally mounted in the rearward portion of the frame member 2 by means of the shaft 73. The arm 71 extends to the forward portion of the device and the free end is provided with an upwardly projecting spike 74. The free end of the arm 71 lies directly below the motor but offset towards the side of the frame opposite to that on which the motor is mounted. Means for swinging the free 10 or spike-carrying end of the arm 71 towards and away from the spikes 65 and 66 comprises a lever 75 pivoted at 76 intermediate its ends and adjacent the lower end to a bracket 77 mounted on the frame. A connecting bar 78 is pivotally connected at 79 at its lower end to arm 71 and to the lower end of the lever at 80. A ratchet 81 is mounted on the frame and is engageable by a dog 82 carried by the lever to lock the lever in any desired position. It will be observed that downward swinging movement of the lever will cause upward swinging movement of the arm 71. Thus the tool may be effectively clamped to a tree 83, as shown in Figure 1.

In order to adjust the clamping mechanism 40 to various sizes of logs or trees, the pivotal connection 80 may be removably mounted in any one of various spaced notches 84 in the connecting bar 78, a spring 85 connected to the bar 78 and arm 71 swinging to maintain engagement of the connection 80 with the respective notch.

While the dimensions of the tool may vary, a tool having the following specific details has been found to be particularly effective:

50 Motor: 1 1/2 horsepower, net weight 33 lbs., 3000 r. p. m.
Ratio of revolutions of driving shaft to crank shaft: 20 to 1.
Stroke of saw: 15 inches.
Cuts per minute: 300.
55 Overall length of frame: 3 feet.
Width of main frame: 1 foot.

60 A tool embodying the above mentioned details does not substantially exceed 50 pounds in gross weight.

Since the heavy end of the tool, carrying the motor and associated parts, is supported by means of the clamping mechanism directly on the work piece, with the lighter end projecting outwardly 65 therefrom, the tool is easily mounted in clamping relation on the workpiece and such clamping relation is rigidly maintained. Moreover, the clamping mechanism, the motor, and the clutch are all arranged in the forward position of the 70 tool so that they are all in easy reach of the operator without changing his position. Thus, the operator may clamp the tool to a work piece, start the motor, and actuate the clutch with a minimum of effort. The bar 78 and pulleys 15 and 75 18 are substantially in line with each other, the

space below the frame forwardly of this line being free to accommodate logs of a wide range of sizes. The clamping bar 71 is located on the lighter side of the machine to provide a more firm support for the machine when mounted on a tree.

The tool is of such light weight that it may be transported by a single operator, and may be, for instance, carried up into a tree for sawing limbs therefrom.

It will be understood that various changes may be made in the structural details of the described device without departing from the spirit and scope of the invention as defined in the appended claims.

I claim:

1. In a sawing tool having a main frame, a crank shaft transversely mounted therein adjacent the rearward end thereof, a sleeve journaled on the crankshaft, an auxiliary frame fixed to the sleeve for pivotal movement about the crankshaft, a saw-carrying carriage supported in the auxiliary frame, and mechanism for imparting reciprocal motion to the carriage, saw loading means comprising a toothed segment fixed to the sleeve, a lever pivoted to the segment and engaging one or other of the teeth of the segment, and a spring having one end connected to the free end of the lever and the other end connected to the main frame at a point spaced forwardly of the crankshaft and urging said lever into engagement with a tooth of said segment.

2. A sawing tool comprising a substantially rectangular main frame having side and end members and a plurality of transverse members fixed to the side members, a shaft journaled transversely in the frame at the rearward end thereof, an auxiliary frame pivotally mounted on one end of the shaft and spaced laterally from the main frame, a carriage reciprocally mounted in the auxiliary frame, a crank arm fixed to the shaft and connected to the carriage, means for driving the shaft to impart reciprocal motion to the carriage including a motor carried in laterally offset relation on the forward end of the main frame, and clamping means for entirely supporting the tool on a work piece comprising a fixed downwardly projecting work-engaging spike carried at one end of the forward end member of the main frame, an arm pivotally mounted on one of said transverse members for lateral swinging movement with respect to the main frame and having its free end in sliding engagement with the forward end member of the main frame, a downwardly projecting work-engaging spike fixed to the free end of said arm, a second arm extending longitudinally of the main frame and having a pair of rearwardly extending legs each pivotally mounted on a rearward portion of a respective side member of the main frame for perpendicular swinging movement with respect thereto, the forward end of the said second arm lying in transversely opposite and laterally offset relation to the motor and having an upwardly projecting work-engaging spike fixed thereto, and a lever pivoted to the main frame and having an adjustable link connection with the forward portion of the second arm to swing the latter about said pivotal mounting.

3. A sawing tool comprising a substantially rectangular main frame having side and end members and a plurality of transverse members fixed to the side members, a shaft journaled transversely in the frame at the rearward end thereof, an auxiliary frame pivotally mounted on

one end of the shaft and spaced laterally from the main frame, a carriage reciprocally mounted in the auxiliary frame, a crank arm fixed to the shaft and connected to the carriage, means for driving the shaft to impart reciprocal motion to the carriage including a motor carried in laterally offset relation on the forward end of the main frame, and clamping means for entirely supporting the tool on a work piece comprising a fixed downwardly projecting work-engaging spike carried at one end of the forward end member of the main frame, an arm pivotally mounted on one of said transverse members for lateral swinging movement with respect to the main frame and having its free end in sliding engagement with the forward end member, a downwardly projecting work-engaging spike fixed to the free end of said arm, a second arm extending longitudinally of the main frame and having its rearwardly extending portion pivotally mounted on a rearward portion of the main frame for perpendicular swinging movement with respect thereto, the forward end of said second arm lying in transversely opposite and laterally offset relation to the motor and having an upwardly projecting work-engaging spike fixed thereto, and a lever pivoted to the main frame and having a link connection with the forward portion of the second arm to swing the latter about said pivotal mounting.

4. A sawing tool comprising a substantially rectangular main frame having side and end members, an auxiliary frame pivotally carried by the main frame, a carriage reciprocally mounted in the auxiliary frame, means for imparting reciprocal motion to the carriage including a motor carried in laterally offset relation on the forward end of the main frame, and clamping means for entirely supporting the tool on a work piece comprising a fixed downwardly projecting work-engaging spike carried by the forward end of the main frame below the motor, and an arm extending longitudinally of the main frame and having a pair of rearwardly extending legs each pivotally mounted on a rearward portion of a respective side member of the main frame for perpendicular swinging movement with respect thereto, the forward end of said arm lying in transversely opposite and laterally offset relation to the motor and having an upwardly projecting work-engaging spike fixed thereto.
